UNITED STATES PATENT OFFICE

163,446

COOKING RANGE

Donald E. Dailey, Bryn Mawr, Pa.

Application April 29, 1950, Serial No. 9,578

Term of patent 3½ years

(Cl. D81—4)

To all whom it may concern:

Be it known that I, Donald E. Dailey, a citizen of the United States of America and a resident of Bryn Mawr, in the county of Delaware and State of Pennsylvania, have invented a new, original, and ornamental Design for a Cooking Range, of which the following is a specification, reference being had to the accompanying drawing, forming a part thereof, in which the figure shows a perspective view of a cooking range embodying my new design.

The left hand side of the cooking range, not shown in the drawing, is substantially the same as the right hand side thereof.

The dominant features of the design reside in the portions shown in full lines.

I claim:

The ornamental design for a cooking range, substantially as shown and described.

DONALD E. DAILEY.
